UNITED STATES PATENT OFFICE.

EDWIN LYFORD GODING, OF SANFORD, MAINE, ASSIGNOR TO O. A. MILLER TREEING MACHINE COMPANY, OF PORTLAND, MAINE, A CORPORATION OF MAINE.

BLOCK-LAST.

956,576.

Specification of Letters Patent.

Patented May 3, 1910.

Application filed June 6, 1902. Serial No. 110,406.

To all whom it may concern:

Be it known that I, EDWIN L. GODING, a citizen of the United States, residing at Sanford, county of York, State of Maine, have invented an Improvement in Block-Lasts, of which the following description, in connection with the accompanying drawings, is a specification, like letters on the drawings representing like parts.

My invention is an improvement in block lasts. Aside from a multitude of different spring devices and other attachments for fastening blocks into place, commonly called "block fasteners," there has been very little invention in block lasts, but they have remained substantially the same for many years.

There are at present two principal forms of blocks or block lasts, one in which the block is sawed out with a blunt and somewhat pointed end, being so made for the purpose of preventing downward and lateral or sidewise movement, and the other form in which the block is sawed out to a thin edge, or scoop shape, as it is termed, in which there is, commonly, a groove and dowel construction for preventing downward and sidewise movement. Both of these, however, require a block fastener of some kind, and when the common spring devices are not employed, it is usual to simply drive in a tack every time the block is put in place.

The main objections to the foregoing are that the repeated tacking rapidly defaces and spoils the last, the last fasteners are expensive, the scoop shape, or thin-edged, block requires the objectionable dowel, and is difficult to put in place because the dowels are in the way, said dowels are constantly getting loose and coming out, the blunt ended or "V-block" often wrinkles and damages the linings when forced into position, and, on the other hand, such lasts when withdrawn (after the removal of the block) catch into the linings and tongues in lace shoes at the corners and edges adjacent the cavity provided for the blunt end of the block.

Accordingly I have invented a new form of block which obviates all the above objections, my block having a shoulder or locking surface co-operating with the body of the last in holding it against movement in any direction when in place in the shoe.

The constructional details and further ad-

vantages of my invention will be pointed out in the course of the following description, reference being had to the accompanying drawings, in which I have illustrated certain preferred forms of my invention.

60

In the drawings, Figure 1 shows in central longitudinal vertical section a last provided with my invention; Fig. 2 is a perspective view of the block thereof; Fig. 3 is a similar sectional view of another form of the invention; Figs. 4 and 5 are similar sectional views showing still other embodiments of the invention.

65

It will be understood that the general construction of the last, aside from the block feature only, may be varied without reference to my invention.

70

Referring now more particularly to Fig. 1, it will be seen that I have provided a block b having a scoop end (which is very desirable for many purposes), but instead of having tacks, dowels, etc., I have simply formed an enlargement or projection b' on the underside of the upper end of the last block, said enlargement terminating in a downwardly extending shoulder b^s at its lower end which abuts against a corresponding cavity in the last for preventing improper downward and other movement, said shoulder b^s forming an acute angle 75 with that part of the longitudinal line of separation between the block and body extending from the shoulder toward the toe of the last, and at the upper end of the enlargement I have provided a shoulder or angular cut b^a , so that when the last is in a shoe, in which position, it will be understood, the upper of the shoe holds the last block firmly in place against the body of the last, there is no liability of the block 80 moving in any direction, as considerable force is required to pull the block out of the shoe, on account of the obstructive shape at b^a . In addition to this, I secure the cord c in a special manner, boring the hole at 85 the line of cut b^a so that a part of the hole forms a notch b^c on the block, the rest of the hole being in the body of the last, as clearly shown in Figs. 1 and 2. The cord occupies this notch and aids in preventing 90 sidewise movement of the last block.

95

Referring now to Fig. 3, where I have shown a block b^e terminating at its lower end b^e in a blunt end or "V-style", it will be seen that instead of providing the par- 100

110

ticular retaining shape shown in Fig. 1 I have provided a shorter projection b^8 , having simply the angular or wedge-shaped cut b^4 at its rear side, and instead of the 5 curved shoulder b^8 shown in Fig. 1 I have simply provided a sharp offset b^9 . This construction is sufficient for many purposes, and particularly so in connection with the 10 V-style of block, inasmuch as the lower end is prevented from lateral shifting by the blunt point, whereas, in the scoop block shown in Fig. 1 there is nothing at the lower extremity of the block to prevent lateral shifting, and hence it is preferable to bring 15 the end b^8 down lower into the last than is required in the form of construction shown in Fig. 3. The shoulder b^4 may be quite high on the last to control the position of the upper end, while shoulder b^8 may be at 20 the shank or waist region of the last. By having the projection b' long and deep as shown it serves to maintain the thin front edge of the block in position so as to be not liable to contact with the complementary 25 shoulder on the last body. It will be noted also that the block is severed from the last body by a single cut laterally continuous and uninterrupted, as distinguished from an irregular line of cleavage, *e. g.*, where 30 there is present a dovetail connection between block and last.

In the construction shown in Fig. 1 it will be noted that the lower surface b^{10} of the enlargement b' is approximately parallel to the crown of the block, thereby permitting the last to move properly in and out of the shoe when being inserted or removed therefrom.

In Fig. 4 I have shown a form of my invention 40 which is particularly adapted to small lasts and certain other places, said form consisting simply in providing a retaining surface in the form of a groove b^{12} in one part and a pin or rounded surface 45 b^{13} in the other part; this pin may be a dowel glued into the last, or it may be formed directly thereon.

In Fig. 5 I have shown still another form 50 of retention, consisting of a protuberance or bunch b^{14} provided on the block and fitting into a corresponding cavity in the body of the last.

From the foregoing it will be readily understood that my invention when considered in its broader aspect resides in providing the contacting surfaces of the block and last with interlocking portions so shaped that they offer sufficient resistance to improper movement for the purpose desired.

For McKay work it is now common to use both the scoop block and the V-style, while the latter only is applicable to turn shoes or turn work, whereas, by this invention, as will be readily apparent to those

skilled in the art, the scoop block may be used for both kinds of work. The forcing in of the scoop block the second time no longer will tend to ruin the edge of the block or loosen the fastening pin, because 70 by my invention no fastening pin or obstruction is present. By having the ledge or interlocking shoulders of considerable depth and extending across the block, as shown, all tendency to twist or shift at one 75 end or the other out of position is prevented. It is not necessary, under ordinary circumstances, that the last block should be absolutely locked positively against movement, inasmuch as the strain of the leather causes 80 the secant surfaces of the block and last to hug tightly together with sufficient firmness to maintain the block in proper position under all ordinary circumstances simply by providing a wedging surface or irregularity 85 on one part coöperating with an oppositely formed surface on the other part.

I prefer the constructions shown in the drawings, particularly that shown in Fig. 1, but do not intend to limit myself thereto 90 inasmuch as many modifications and changes may be resorted to in view of the foregoing description without departing from the spirit and scope of my invention.

Having described my invention, what I 95 claim as new and desire to secure by Letters Patent of the United States, is:—

1. A last, comprising complementary shaped instep block and body, the block having upon its body engaging surface an outwardly projecting portion extending transversely from side to side of the block and arranged to resist upward movement of the block on the body longitudinally of the last.

2. A last comprising complementary shaped block and body, said block and body having formed integrally therewith interlocking portions intermediate the ends of the block arranged to resist upward movement of the block upon the body.

3. A last comprising complementary shaped instep block and body, the block having formed integrally therewith an outwardly extending projection on its body engaging surface arranged to resist upward movement of the block upon the body.

4. A last comprising complementary shaped block and body, the block having formed integrally therewith an outwardly projecting portion on its body engaging surface constructed to resist upward movement of the block upon the body, said portion being provided with a forwardly extending shoulder at its lower extremity arranged to resist downward movement of the block on the body.

5. A block last, comprising complementary shaped block and body, the upper portion of the contacting surfaces of the two members immediately below the upper end

of the block being deflected to form an obstruction to the removal of the block.

6. A block last comprising complementary shaped block and body, and a cord 5 lying between and extending into engaging portions of block and body at the extreme upper part of block and body to prevent relative lateral movement of block and body.

7. A block last comprising a block and a body, secured together by a cord, one end of 10 which is secured in the block and the other end secured in the body at the surface of contact of block and body, and projecting into the block to prevent lateral shifting 15 movement thereof, the portion of the cord intermediate said ends being arranged exteriorly to the last.

8. A last comprising complementary shaped block and body, the block having 20 formed integrally therewith an outwardly projecting portion on its body engaging surface, constructed to resist upward movement of the block upon the body, said portion being provided with a forwardly extending shoulder at its lower extremity, said 25 shoulder at its side next the instep forming an acute angle with the longitudinal line of

separation between block and body extending from the shoulder toward the toe of the last.

9. A block last having the secant surfaces between the block and last formed with an offset or resistance surface for preventing rearward or outward movement of the block when in place in a shoe, said block and last 30 being secured together by a cord, one end of which is secured in the block and the other end is secured in the last body at the meeting top edges of the last and last block and projecting into the latter for preventing lateral 35 shifting movement thereof.

10. A last, comprising complementary shaped block and body, said block and body having formed upon their contacting surfaces intermediate the ends of the block in- 40 terlocking portions arranged to resist upward movement of the block upon the body.

In testimony whereof, I have signed my name to this specification, in the presence of two subscribing witnesses.

EDWIN LYFORD GODING.
